US0D1081717S

(12) **United States Design Patent** (10) **Patent No.:** **US D1,081,717 S**
(45) **Date of Patent:** **** Jul. 1, 2025**

(54) **DISPLAY SCREEN WITH ICON GROUP AND DISPLAY SCREEN WITH ICON SET**

(71) Applicant: **Microsoft Corporation**, Redmond, WA (US)

(72) Inventors: **Joseph Wheeler**, Sammamish, WA (US); **Yi-An Chien**, Bellevue, WA (US); **Joann Marie Maisonet**, Kirkland, WA (US)

(73) Assignee: **Microsoft Corporation**, Redmond, WA (US)

(**) Term: **15 Years**

(21) Appl. No.: **29/893,645**

(22) Filed: **Jun. 1, 2023**

Related U.S. Application Data

(62) Division of application No. 29/731,750, filed on Apr. 17, 2020, now Pat. No. Des. 991,975.

CLAIM

The ornamental design for a display screen with icon group and display screen with icon set as shown and described.

DESCRIPTION

FIG. 1 is a front view of a display screen with icon group showing our new design; and,

FIG. 2 is a front view of a display screen with icon set showing our new design.

The broken line showing of portions of the display screen forms no part of the claimed design. The bracket in FIG. 2 indicates an icon set and forms no part of the claimed design.
